UNITED STATES PATENT OFFICE.

ARTEMAS B. EDMANDS, OF MILFORD, MASSACHUSETTS, ASSIGNOR TO
GEORGE DRAPER & SONS, OF SAME PLACE.

SPINNING-MACHINE.

SPECIFICATION forming part of Letters Patent No. 317,323, dated May 5, 1885.

Application filed February 1, 1884. (No model.)

To all whom it may concern:

Be it known that I, ARTEMAS B. EDMANDS, of Milford, county of Worcester, State of Massachusetts, have invented an Improvement in 5 Spinning-Machines, of which the following description, in connection with the accompanying drawings, is a specification, like letters on the drawings representing like parts.

This invention relates to that class of spinning-machines called "speeders," wherein the bobbin or spool is carried by a quill so connected with the spindle and flier as to enable the bobbin or spool to be doffed at any position occupied by the spindle in its traverse.

15 My invention consists, essentially, in the combination, with a speeder-flier and the removable bobbin-receiving quill, of a pivoted quill-holding latch, as will be hereinafter described; also, in a speeder-flier, a slotted 20 quill, and bushing, and means to connect the upper end of the quill with the flier and the spindle, combined with a sleeve, buttons thereon, and with a gear, and with means to connect it with the said sleeve, for the purposes 25 to be hereinafter stated; also, in a flier and a slotted quill, and means to engage both ends of and retain the same in the flier, combined with a flat spindle and means to drive or rotate it, the said spindle driving the quill and 30 bobbin thereon in unison with it, the flat spindle enabling the bobbin to be doffed at any position which it may occupy in the traverse, substantially as will be described.

35 My invention also consists in other features, which will be further set forth in the claims at the end of the specification.

Figure 1 represents in elevation one of my improved spindles with a flier and quill, the said parts being supported, as usual, by bolster and spindle rails. Fig. 2, on a larger 40 scale, represents the parts shown in Fig. 1 above the dotted line *y* *y*, the lower part of the quill, the neck of the flier, the bushing, sleeve, gear, and bolster-rail being broken out to better show the parts, the said figure showing a 45 bobbin in dotted lines. Fig. 6, on a larger scale, represents the parts of Fig. 1 below the dotted line *y* *y*, the tubular shaft, the gear *f*, and bushing *g* being broken out, the parts 50 shown in Fig. 6 being in continuation of those shown in Fig. 2. Fig. 3 is a right-hand side

view of Fig. 2. Fig. 3^a is a right-hand side view of Fig. 3. Fig. 4 is a partial section of Fig. 1 on the dotted line *x* *x*, looking upward, the quill being omitted. Fig. 5 is a section of 55 the quill-holding latch. Fig. 7 is a sectional detail and bottom end view of the bushing at the lower end of the quill; Fig. 8, a top view, section, and under side view of the button, to be described, located at the lower end of the 60 tubular shaft *e*. Fig. 9 is top view of the quill-holding latch removed from the flier, and Fig. 10 a vertical section taken through the nose of the flier and the latch and its pivot-pin, the spring being removed. 65

The flier *A*, having at its upper end a nose and journal, *a*, adapted to be held, as usual, in a top bearing, has at its lower end a collar, *a*², provided with one or more projections, *a*³, (see Figs. 2 and 3,) which enter notches in the 70 head of the sleeve *a*⁴, extended through the bolster *a*⁵ in the bolster-rail *B*, the said sleeve having an attached bevel-gear, *a*⁶, which will be engaged and driven, as usual, in speeder-frames by a bevel-gear. 75

The flier, at its upper end, is provided with a quill-holder, *b*, made as a pivoted latch, the rearwardly-extended arms of which are attached to a bolt, *b*', entered loosely through ears of a backward extension, *b*², forming a 80 rigid and preferably integral part of the upper yoke, *b*³, of the flier, the end of the bolt entering a grooved boss, 40, forming part of the holder, and being held therein by a pin, 44, driven through a hole in the bolt, the end 85 of the pin shown in black, Figs. 4 and 9, being held by a slot in the said boss 40.

The bolt *b*' is provided (see Figs. 3 and 10) with a projection, *b*²', to which is attached the inner end of a steel spring, *b*⁴, the outer end 90 of the said spring being made to engage a pin, 42, within the said backward extension, as shown in said Fig. 3.

The free end of the latch, curved slightly upward and normally pressed downward by 95 the said spring, is provided with a flaring groove, 3, (see Fig. 4,) and a tongue, 5, which latter extends backward into the fork or slot formed by cutting away the downwardly-extended sleeve, like central hub 6 of the said 100 yoke *b*³.

In the yoke *b*³ is an abutment, 7, which forms

a shoulder to keep the quill C down upon the part, to be described, which rotates it. The groove 3 acts to guide and direct the upper end or head, c^2 , of the quill C as the same is brought into line vertically with relation to the axis of rotation of the flier, as when the roving is being wound upon the bobbin D, (shown in dotted lines, Fig. 2.) The latch yields as the quill is moved from its dotted-line position, Fig. 3, into its full-line position, and after the arrival of the quill into its full-line position the latch is forced down by the spring to lock the quill in place. The quill is slotted at one side for upward of one-half its length (see Figs. 1 and 2) for the passage through it of the bobbin or spool driving projection 8 (see Fig. 3) of the spindle E, preferably made as a flat bar of steel supported at its lower end on a vertically movable foot-step or traverse-rail, F, the projection 8 entering a notch in the bobbin or spool, as usual.

The lower end of the quill has a bushing, 10, inserted into it, which is provided with a hole the same in cross-section as the spindle, and the said bushing has a notch, 22, (see Figs. 2 and 7,) which is entered by a projection, 12, at the upper side of a button or plate, 13, (see Fig. 8,) having a neck, 23, at its under side to enter and be attached to the upper end of a tubular shaft, e, the said button 13 having a hole the same in cross-section as the spindle E.

The tubular shaft e, passed through the sleeve a^4 , extended downward from the flier, has at its lower end (see Figs. 6 and 3^a) an attached bevel-gear, f, having its shank or neck f' extended down through a secondary bolster, g, fixed on the auxiliary bolster-rail B², and at its lower end the said tubular shaft has a button, 15, (see Figs. 6 and 3^a), of substantially the shape of the button 13, the button 15 being provided with a central opening shaped to correspond in cross-section with the spindle E.

The gear f has a spline, 16, which enters a slot in the tubular shaft e, so that as the said gear is rotated or driven by another bevel-gear (not shown) on a horizontal shaft the said gear f will rotate the shaft e, and it, by the button 15, will rotate the spindle E, while the button 13 will rotate the quill.

When it is desired to doff a bobbin, the operator stops the flier with the presser at its rear side, and seizing the bobbin the operator pushes or lifts the latter on the quill until it strikes the latch, and at the same time the operator, by pulling the bobbin outward, the latch having been lifted, pulls the quill out from the flier, and the bobbin is then pulled from the quill.

The presser h may be of any usual construction. I have shown it attached to a rod, h', held in bearings in the flier-leg and having at its lower end a weight, h².

By slotting the quill and making the spindle flat, as shown, it is possible to tip the quill

out of the flier at any position of the traverse. If the spindle were round, as heretofore, commencing near or below the end 8, and the said spindle filled the quill, it would not be possible to tip the quill outward to doff a bobbin so long as the round part of the spindle remained within the quill, and hence with a round spindle the doffing could take place only when the presser is at the top of the bobbin.

I am aware that it is not new to hold the quill by a sliding bolt, as in United States Patent No. 228,809.

I claim—

1. The speeder-flier and its pivoted quill-holding latch b, combined with the bobbin-receiving quill, substantially as and for the purpose described.

2. The bobbin-receiving quill and the speeder-flier having its upper yoke provided with a downwardly-extended sleeve-like hub slotted at one side for the passage of the upper end or head of the quill combined with the pivoted latch having a central opening to receive and hold the upper end of the quill, substantially as described.

3. The speeder-flier and quill supported thereby at its lower end, combined with a latch and a spring to act upon and hold the same, as described, whereby the latch may rise to permit the passage of the quill under it into central position with relation to the flier, and thereafter act to engage the upper end of the quill and retain it in the flier, substantially as described.

4. The flier, the slotted quill, its bushing, means to connect the upper end of the quill with the flier, and the spindle E, combined with the sleeve e, buttons 12 and 15, and with the gear f, and means to connect it with the said sleeve, substantially as described.

5. The flier and the latch b, pivoted thereto, and provided with the groove 3, combined with the quill, to operate substantially as described.

6. The flier having the slotted downwardly-extended hub 6 and the latch b, pivoted thereto, and provided with the groove 3 and tongue 5, combined with the quill, substantially as described.

7. The flier and the slotted quill and means to engage both ends of and retain the same in the flier, combined with a flat spindle, and means to drive or rotate it, the said spindle driving the quill and bobbin thereon in unison with it, substantially as described, whereby the bobbin may be doffed at any position of the bobbin or of the traverse, substantially as described.

In testimony whereof I have signed my name to this specification in the presence of two subscribing witnesses.
